(57) **CLAIM**

The ornamental design for a hand truck side rail, as shown and described.

DESCRIPTION

FIG. 1 is a perspective view of the hand truck side rails showing my new design, the broken line illustration of the other components of the hand truck are for illustrative purposes only and form no part of the claimed design; FIG. 2 is an end elevation view of the hand truck side rail on an enlarged scale;

FIG. 3 is an enlarged fragmentary side elevation view thereof, the opposite side view being a mirror image of that shown;

FIG. 4 is an enlarged fragmentary rear elevation view thereof; and,

FIG. 5 is an enlarged fragmentary front elevation view thereof.
